(57) **CLAIM**

The ornamental design for a bag, as shown and described.

DESCRIPTION

1. Bag
1.1 : Perspective
1.2 : Front
1.3 : Back
1.4 : Right
1.5 : Left
1.6 : Top
1.7 : Bottom
1.1 is a top, front, and right side perspective view of bags embodying our new design; **1.2** is a front elevation view thereof; **1.3** is a rear elevation view thereof; **1.4** is a right side elevation view thereof; **1.5** is a left side elevation view thereof; **1.6** is a top plan view thereof; and **1.7** is a bottom plan view thereof; this article is a bag that stores various items such as wallets, smartphones, cosmetics, accessories, etc; it is portable by using a strap connected to the main body, and is used with being attached to and detached from electric kickboards and bicycles.
